UNITED STATES PATENT OFFICE.

WILLIAM E. HASKELL, OF BRATTLEBORO, VERMONT, ASSIGNOR TO ESTEY ORGAN COMPANY, OF BRATTLEBORO, VERMONT, A CORPORATION OF VERMONT.

STRAIGHT-LIFT PNEUMATIC.

No. 923,263.

Specification of Letter Patent.

Patented June 1, 1909.

Application filed November 22, 1907. Serial No. 403,416.

To all whom it may concern:

Be it known that I, WILLIAM E. HASKELL, a citizen of the United States, residing at Brattleboro, in the county of Windham and State of Vermont, have invented certain new and useful Improvements in Straight-Lift Pneumatics, of which the following is a specification.

The invention relates to the small bellows or "pneumatics" which are used in wind musical instruments, such as organs, for the purpose of pneumatically causing mechanical movement. Such pneumatics comprise a base and a movable board, which are united together by a flexible membrane, serving as flexible walls to inclose an expandible and contractible space or chamber between the base and movable board into which air may be admitted and exhausted. These pneumatics frequently require to be placed very close to each other, and difficulty has arisen through interference between adjacent pneumatics. These pneumatics frequently are placed in such situation that they are called upon to receive interior air pressure greater than the external air pressure, and it frequently happens that the bellows folds of the uniting membrane are blown outwardly by the greater internal air pressure so that the folds of the membrane project beyond the margins of the base and movable board and there interfere with the movement of adjacent pneumatics and prevent their proper movement. Even if there is enough space and there is no danger of interfering with its neighbor, the outward bulging of the fabric prevents restoration to proper position when the pressure is released. In order, as far as possible, to overcome this difficulty a slightly stiffer material has been used than would otherwise be necessary and the folds are tightly pressed to thereby gain some resistance to the pressure from within. The fabric of which these flexible walls have been constructed is usually a rubber coated mull or thin cotton. The coating is necessarily thin and of inferior quality, as it cannot be sufficiently vulcanized to make it reliable. If vulcanized it does not take the fold without being baked, all of which tends to make it stiffer. The tightly pressed folds wear rapidly and soon render the pneumatic leaky and unsatisfactory in action. In spite of all precautions, prolonged

use, with excess of air pressure on the inside, results in a degeneration of the straight lines of the folds into outwardly bulging curves and the fabric becomes set in this shape, forming a springy buffer-like resistance to the contracted state which renders the pneumatic sluggish in its operation if it operate at all.

The primary object of this invention is to provide a pneumatic with the flexible walls of the uniting membrane disposed outwardly instead of inwardly, giving the appearance when inflated of a pillow; the base and movable board being glued or otherwise attached to the exterior lower and upper surfaces respectively of the thus formed pillow, which does away with the present necessary internal creases in the membrane walls and by so doing makes it possible to use a more flexible material such as very soft leather, preferably thin skiver goat skin, thereby greatly increasing the sensitiveness of its normal function; and also, by virtue of its already outwardly disposed walls, precludes, in case the internal air pressure is greater than the external, the possibility of blowing inside out. Hence there is no opportunity for failure to act, nor for interference with neighboring pneumatics. The maximum extension of these outwardly disposed walls either inflated or deflated is not greater than that of the edges of the base and movable board of the old style pneumatics with equal power. Although the membrane walls extend outwardly beyond the base and movable board, the new style pneumatic occupies no more space than the old style. Inflation tends rather to diminish the lateral width without the possibility of increasing it by "blowing out."

When deflated the upper and lower inner surfaces of the flexible membrane come together and lie flatly without forming other creases than form the four edges of the rectangular shape, which edges project outwardly beyond the edges of the base and movable board.

The present improvements are illustrated in the accompanying drawings, wherein—

Figure 1, is a top view of the new pneumatic. Fig. 2, is a longitudinal section of the pneumatic when inflated. Fig. 3, is a cross section of the pneumatic when inflated. A, is the movable top board; B, is the

base; C, is the membrane; D, is one of the small copper clips used in this case to fasten the ends of the membrane; E, is the small hole in the top board for the sticker or 5 tracker as the case may be, and F, is the hole in the base through which air is admitted to the interior of the pneumatic. The pneumatic is of the type wherein the entire top board moves bodily and squarely to and 10 from the base (commonly called "straight lift" pneumatics), to which the present improvements are applicable. The flexible membrane C, unites the base and movable board, and provides, by its pillow-like construction, an expandible and contractible 15 chamber between the base and movable board.

In making the new pneumatic, a piece of soft leather, preferably soft skiver goat skin, 20 is cut into the desired length and width, and the ends are overlapped and glued together (as shown in Fig. 3), and the whole is then pressed flat. The two open ends are then closed by fastening on the copper clips D, 25 or by gluing or other suitable means. The base B, and movable board A, are then glued to the bottom and top of the folded membrane. The membrane has holes registering with the holes E, and F. 30 The action of the new pneumatic is in effect similar to that of those which have been in extensive use in wind musical instruments. The air on being admitted to the chamber through the aperture F, tends 35 to fill the chamber, thereby separating the movable board A from the base B, and giving the membrane C, the appearance of a pillow. The edges of the copper clips D, as shown, are bent outward presenting curved 40 bearing surfaces to prevent cutting into and injuring the delicate material of which the flexible membrane is composed. The air being allowed to escape, the upper and lower interior surfaces of the membrane again 45 come into contact with each other as usual in the deflated state. No internal bellows folds prevent this complete return. The use of a very soft leather without bellows folds obviates the possibility of such a condition 50 as in the old pneumatics where stiffness, long use, and prolonged internal air pressure cause the fabric of the walls to set in bulging curves offering a resistance to deflation. 55 As the result of this improvement membranes of the pneumatics may be made of very delicate material so as to quickly respond to differences in pressure, will act rapidly even on a long tube where the friction of the tube absorbs a great deal of the 60 effect of the air motion, and every possibility

of the accident of "blowing out" is obviated because the walls are already outwardly disposed.

The total area of the new pneumatic with its outwardly extending membrane folds is 65 no greater than that of old pneumatics of equal power. The drawings illustrate the pneumatic on an enlarged scale.

I claim:

1. A straight-lift pneumatic composed of 70 a base; a movable board; a flexible membrane uniting said base and movable board, said membrane being a soft flexible fabric folded flat, its two folded edges extending beyond two opposite edges of the board and 75 base, the two lapped edges of the membrane being glued together and located between the base and board, and the two open ends of the folded fabric extending beyond the other two opposite sides of the base and 80 board; and clamps at the open ends of the folded fabric which cover the ends and make them air-tight, said membrane constituting the extensible and contractible air chamber of the pneumatic, and being substantially pillowlike in appearance and presenting no internal folds.

2. A straight-lift pneumatic composed of 85 a base; a movable board; a flexible fabric uniting said base and movable board, said fabric being folded flat, its two folded edges extending beyond two opposite edges of the board and base, the two lapped edges of the membrane being located between the base and board, and the two open ends of the 90 folded fabric extending beyond the other two opposite sides of the base and board; and means for closing the open ends of the fabric making them air-tight, said fabric constituting the extensible and contractible 95 air chamber of the pneumatic, and presenting no internal folds.

3. A straight-lift pneumatic composed of 100 a base; a movable board; a flexible fabric uniting said base and movable board, said 105 fabric being folded flat and extending outwardly beyond all four edges of the board and base and constituting the extensible and contractible air chamber of the pneumatic, and presenting no internal folds; and means 110 for closing the open ends of the fabric making them air-tight.

In witness whereof, I have hereunto signed my name in the presence of two subscribing witnesses.

WILLIAM E. HASKELL.
